UNITED STATES PATENT OFFICE

CHARLES M. LOEPFE, OF ST. LOUIS, MISSOURI, ASSIGNOR TO COTTONWOOD FIBER COMPANY, OF ST. LOUIS, MISSOURI, A CORPORATION OF MISSOURI

OIL BURNER

Application filed April 21, 1928. Serial No. 271,690.

This invention relates to oil burners.

An object of the invention is to provide an improved oil burner having a pipe for conducting oil toward the burner arranged 5 in a novel relationship so that the oil will be subjected to the heat of the burner and more efficiently vaporized for combustion.

Another object of the invention is to provide an oil burner having an improved valve 10 device for controlling and regulating the same.

Another object of the invention is to provide an oil burner possessing all of the improvements and advantages herein 15 disclosed, reference being made to the drawings in which.

Fig. 1 is a plan view of my improved burner.

Fig. 2 is a front side elevation.

20 Fig. 3 is a sectional view approximately on the line 3—3 of Fig. 1.

Fig. 4 is an enlarged sectional view showing one of the burner openings and its controlling disc on the inclined front side of 25 the burner.

Fig. 5 is an enlarged sectional view showing one of the burner openings through the top of the burner and the manner in which the disc is held in position.

30 Fig. 6 is an enlarged sectional view approximately on the line 6—6 of Fig. 1 showing the construction of the valve.

Fig. 7 is a cross sectional view approximately on the line 7—7 of Fig. 6.

35 Fig. 8 is an enlarged detail view of the valve.

Fig. 9 is a detail view partly in section showing the screen strainer device for the oil.

Fig. 10 is a cross sectional view on the 40 line 10—10 of Fig. 9.

As shown, the invention is supported between the side walls 1 and 2 of a frame. The burner proper comprises a hollow member including upwardly diverging bottom 45 walls 3 from the upper edges of which the upwardly converging side walls 4 extend to integral union with an approximately horizontal top wall 5 and with an end wall 6 having a gas inlet opening 7 to the inside 50 of the enclosure formed by said walls. The

opposite end of the enclosure formed by said walls comprises an extension 8 including an upwardly and inwardly inclined top wall 9. The top wall 5 of the enclosure is surrounded by a vertical flange 10 extending upwardly above the plane of the top wall 5 and having a notch 11, the bottom of which is in continuation of the upper surface of the top wall 5 and which notch opens toward the inclined wall 9. The top 55 wall 5 is formed with a horizontal series of holes 12 around each of which rises a flange 13, which flanges are integral with the top wall 5 of the burner. Each hole 12 is also surrounded by a shoulder 14, and upon the shoulder 14 within each hole and within each flange 13 a disc 15 is seated. The flanges 13 are rolled or swaged upon the edges of the discs 15 (Fig. 5), thereby rigidly securing and retaining said discs in 60 position.

The inclined front wall 4 is formed with a longitudinal series of small outlet openings 16 (Fig. 4) forming communications with dished recesses 17 in the front wall 75 4, which recesses are surrounded by flanges 18. In each of the dished recesses 17 a burner disc 19 is seated and the flanges 18 are rolled or swaged upon the edges of the burner discs 19, thus rigidly securing 80 and retaining said discs in position and leaving the enlarged concavities 17 at the inner sides of said discs having communication with the interior of the burner device through the holes 16. These burner 85 discs 19 are arranged in a novel relationship to the burner discs 15, as will be readily understood by reference to Fig. 1 wherein it will be seen that the flange 10 above each of the burner discs 19 has a notch 90 20 extending downwardly to the surface of the top wall 5. This obviously facilitates combustion and ignition of the gas passing from the burner discs 19, whereby the oil passing to the apparatus is subjected 95 to heat.

Similarly the inclined wall 9 is equipped with a disc 21 in all respects similar to the discs 19 and likewise seated in a concave recess having a restricted opening to 100

the inside of the device. Ignition of the gas passing from the burner disc 21 is assured because of the presence of the notch 11 adjacent to the disc 15 at the end of the series in the top wall. All of the discs 15, 19 and 21 have numerous holes through which the gas passes.

Oil is supplied to the device through a pipe or tube 22 extending under the burner device above described and opening upwardly into the lower end of a vertical pipe 23 into a pipe 24 enclosing a roll of screen 25 whereby the oil is strained and freed from impurities. The pipe 24 has a detachable end section 26 to which the screen 25 is secured and which may be detached to withdraw the screen for purposes of cleaning and repair. The pipe 24 is supported on frame members 27 formed integral or rigid with the burner unit and extends approximately horizontally slightly above and to the front of the burner discs 19 so that the strained oil passing through said pipe 24 is subjected to the intense heat of the burner. The end of the pipe 24 is connected to one arm of a four-way fitting 28, one arm of which has a removable cap 29 and another arm of which has a detachable connection 30, which parts are made detachable in order to facilitate cleaning the oil pipes. From the fourth arm of the four-way fitting 28 a pipe section 31 extends across slightly above and adjacent to the end burner disc 21 so that the oil passing through said pipe section 31 from the pipe 24 remains subjected to the heat of the burner.

The pipe 31 opens into a hollow member 32 having at its outer end a tapered threaded extension 33 and at its inner end a disc 34 having a large central hole and an annular series of restricted holes 35. A member 36 is screwed onto the end of the hollow member 32 in which the disc 34 is mounted and in its outer end has a conical recess 37 formed in axial alignment with the large central hole through the disc 34 and having its apex opening into a small gas outlet 38. The outer end of the member 36 is beveled and fits closely within a correspondingly shaped recess in the end of a pipe 39. This pipe 39 extends along the rear of the device in communication with a chamber 40 which has communication through the hole 7 to the interior of the burner. The chamber 40 is equipped with a drain device 41 (Fig. 2).

The valve for controlling the passage of gas to the burner is best shown in Fig. 6 and comprises a stem 42 extending through the extension 33 and axially through the hollow member 32 and through the large hole in the disc 34 and into the chamber 36. A valve body 43 has detachable threaded connection with the end of

the rod 42 and has a rounded extremity insertable within and withdrawable from the concave recess 37 to cooperate with the machined wall of said recess to control and regulate the passage of gas. A valve element 44 is screwed into the end of the valve body 43 and includes a needle valve portion 45 at its outer end which is united with the main element 44 by a conical portion 46. When the valve is completely closed the rounded machined end of the valve body 43 seats against the wall of the recess 37 while the conical portion 46 contacts with the apex portion of the conical recess 37 and the needle valve 45 extends through the restricted opening 38. It will be seen that by operation of the rod 42 to open and to close this valve the needle valve part 45 will keep the opening 38 open and prevent it from becoming clogged.

The outer end of the valve rod 42 extends through and beyond the extension 33 into a fitting 47 and through a hole in a partition 48 in said fitting. At the outer side of said partition 48 in the fitting 47 the valve rod 42 has swivel connection 49 with a valve operating device 50. The valve operating device 50 has an enlarged threaded portion 51 screwed within a threaded opening in a fixture 52 attached to the outer end of the fitting 47 and is equipped on its outer end with a handle 53 whereby said device may be operated. This swivel connection 49 whereby the operating device 50 is connected with the rod 42 constitutes a highly important feature of the invention, since the rod 42 is positively operated thereby, but is not subjected to any lateral strains or stresses and hence does not become jammed or distorted, but will operate freely under nearly all conditions of use of the burner.

The chamber 36 is located adjacent to a burner outlet disc 54 so that most of any oil which might become trapped in said chamber will be vaporized and caused to pass on to the burner. A function of the disc 54 is to subject the chamber 36 to the heat of the flame at said disc 54 in order to vaporize any oil that might pass into said chamber 36 from the connections previously described. As will be seen by reference to Fig. 6 of the drawings, the chamber 36 may receive and contain any oil passing thereto from the hollow member 32. As shown in Fig. 1, the chamber 36 is adjacent to the disc 54 so that the heat of the flame at the disc 34 will be applied directly against the chamber 36 to effect vaporization of oil received and contained in said chamber 36.

A dial plate 55 is clamped between the fixture 52 and the fitting 47 and may be read with respect to the position of the handle 43 to indicate generally the positions of the valve.

A handle 56 is provided for operation and

adjustment of a closure 57 for an air inlet 58 to the pipe 39 beyond the end of the chamber 36. By manipulation of the handle 56 the closure 57 may be operated and 5 adjusted to regulate the amount of air admitted to the pipe 39 for mixture with the gas.

A pan 59 may be mounted at one end of the device below the pipes 26 and 31 and 10 below the element 32 for use as a receptacle to contain a wick element 60 designed and arranged to be impregnated with combustible liquid supplied thereto through pipes 61 from a cup 62. When the wick 15 element 60 becomes saturated with the combustible liquid it may be ignited to heat the pipes 26 and 31 and the element 32 so as to ignite the oil passing therethrough toward the burner. After the gas thus created be- 20 comes ignited as it passes from the burner the wick may be extinguished, as the burner is then self-controlled.

In use, the wick 60 is permanently ignited to heat and vaporize oil passing to the 25 burner. The valve handle 53 is then opened to permit a desired amount of gas to pass to the burner discs for ignition. By adjustment and regulation of the closure 57 a proper mixture of air and gas may be ob- 30 tained. The pipes 26 and 31 will be kept hot by ignition of gas passing from the discs 19 and 21 and any oil passing into the chamber 36 will be vaporized by the flame at the burner disc 54. The valve is easily 35 operative at all times and does not become jammed or distorted to such an extent that it is difficult to operate, since the swivel connection 49 maintains the parts 42 and 50 in conditions of easy operation.

40 I am aware that the construction and arrangement of the parts may be varied within equivalent limits without departure from the nature and principle of the invention. I do not restrict myself unessentially, but 45 what I claim and desire to secure by Letters Patent is:—

1. In a gas burner, an enclosure having a top wall and inclined side walls, an upwardly extending flange around said top wall 50 having notches therein extending to the surface of said top wall, perforated gas outlet discs secured in one of said inclined side walls below said notches, perforated discs secured in said top wall, a pipe extending 55 adjacent to the perforated discs in said side wall, connections for conducting gas from said pipe into said enclosure, and a valve in said connections controlling the passage of gas from said pipe to said connections.

60 2. In a gas burner, an enclosure having a top wall and inclined side walls, an upwardly extending flange around said top wall having notches therein extending to the surface of said top wall, perforated gas outlet 65 discs secured in one of said inclined side

walls below said notches, perforated discs secured in said top wall, a pipe extending adjacent to the perforated discs in said side wall, connections for conducting gas from said pipe into said enclosure, a valve in said connections controlling the passage of gas from said pipe to said connections, and means for regulating admission of air to 70 said connections.

3. A gas burner comprising an enclosure 75 having side walls and a top wall, a series of burner discs in said top wall, a series of burner discs in one of said side walls, an inclined wall beyond one end of said top wall, a burner disc in said inclined wall near one end of said enclosure, a pipe extending adjacent to said discs in said side wall, a pipe extending at an angle from said first pipe and adjacent to said last named burner disc, a device for conducting gas into said enclosure, connections for conducting gas from 80 said last named pipe to said device, and a valve controlling passage of gas from said last named pipe to said device.

4. A gas burner comprising an enclosure 90 having side walls and a top wall, a series of burner discs in said top wall, a series of burner discs in one of said side walls, a burner disc near one end of said enclosure, pipe connections extending adjacent to said 95 discs in said side wall and to said disc near one end of said enclosure, a device for conducting gas into said enclosure, connections for conducting gas from said pipe connections to said device, a valve controlling passage of gas from 100 said pipe connections to said device, a chamber for trapping oil passing from said connections to said device, and a burner disc in said enclosure adjacent to 105 said chamber.

5. An oil burner comprising an enclosure 110 for gas having gas outlet openings through one lateral side and also having gas outlet openings through the top, an oil conducting pipe supported adjacent to said openings through the lateral sides and subjected to the flames of the burning gas at said last named openings, a pipe at the opposite side of said enclosure from said first pipe and opening into said enclosure, a device opening into one end of said second pipe for admitting gas thereto, a pipe extending transversely above one end of said enclosure adjacent to one of said openings through the top for conducting gas from said first pipe 120 to said device and being subjected to the heat of the burning gas at said last named opening, and a valve mounted in said device controlling passage of gas therefrom to said second pipe.

125 6. An oil burner comprising an enclosure for gas having gas outlet openings through one lateral side and also having gas outlet openings through the top, an oil conducting pipe supported approximately parallel with 130

one side of said enclosure and subjected to the flames of the burning gas at said openings through said lateral side of said enclosure, a hollow member near the opposite side of said enclosure from said pipe, a pipe extending transversely above one end of said enclosure adjacent to one of said openings through the top for conducting gas from said pipe to said hollow member and being subjected to the heat of the burning gas at said last named opening, a pipe opening into the opposite end of said enclosure, a chamber forming communication from said hollow member to said last named pipe, and a valve controlling passage of gas from said chamber to said last named pipe.

7. An oil burner comprising an enclosure for gas having gas outlet openings in its upper side and also having gas outlet openings through one lateral side, an oil conducting pipe supported near one side of said enclosure and subjected to the heat of the burning gas issuing from said lateral side openings, a pipe supported near the opposite side of said enclosure and opening into one end of said enclosure, means for conducting gas from said first pipe to said second pipe near the opposite end of said enclosure from which said second pipe opens into said enclosure, a pipe extending angularly from said first pipe to said means and transversely of the axis of said enclosure, and a valve controlling passage of gas from said first pipe into said second pipe.

8. An oil burner comprising an enclosure for gas having gas outlet openings in its upper side and having an inclined wall at one end provided with a gas outlet opening and also having lateral gas outlet openings, an oil conducting pipe supported at one side of said enclosure and subjected to the heat of the burning gas issuing from said lateral openings, a pipe supported near the opposite side of said enclosure and opening into the end of said enclosure opposite from said inclined wall, a branch pipe extending from said first pipe transversely above said inclined wall adjacent to said opening in said inclined wall, and means controlling passage of gas from said branch pipe to said second pipe.

9. An oil burner comprising an enclosure for gas having gas outlet openings in its upper side and having an inclined wall at one end provided with a gas outlet opening and also having lateral gas outlet openings, an oil conducting pipe supported at one side of said enclosure and subjected to the heat of the burning gas issuing from said lateral openings, a pipe supported near the opposite side of said enclosure and opening into the end of said enclosure opposite from said inclined wall, a branch pipe extending from said first pipe transversely above said inclined wall adjacent to said opening in said

inclined wall, a hollow member receiving gas from said branch pipe, a chamber forming communication from said hollow member to said second pipe, a perforated disc controlling passage of gas from said hollow member to said chamber, and a valve controlling passage of gas from said chamber to said second pipe.
